UNITED STATES PATENT OFFICE.

JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

CAN-BODY RE-FORMER.

1,152,312.

Specification of Letters Patent. Patented Aug. 31, 1915.

Application filed April 16, 1914. Serial No. 332,260.

To all whom it may concern:

Be it known that I, JAMES ALFRED GRAY, a citizen of the United States, residing in the city and county of San Francisco and State of California, have invented certain new and useful Improvements in Can-Body Re-Formers, of which the following is a specification.

The present invention relates to can body reforming or reshaping machines adapted for operating on can bodies which have been compressed or flattened to a substantially oval form for convenience in shipment, and which it is desired to again reshape to a cylindrical form for the filling thereof and the placing of ends thereon.

The invention has for its principal objects to provide a machine of the above mentioned type which is capable of gradually reforming to a cylindrical form substantially flat can bodies, without cracking or injury to the metal or seam thereof; one into which the substantially flat can bodies are automatically fed and from which said can bodies are discharged in a cylindrical form; one through which the can bodies as reformed are carried by the reforming mechanism; and one which is capable of rapidly operating on can bodies, thus reducing to a minimum the cost of reforming the same.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the appended claims may be resorted to without departing from the spirit or sacrificing any of the advantages of the invention.

To more fully comprehend the invention, reference is directed to the accompanying drawings, wherein—

Figure 1 is a side elevation of my improved machine partly broken away, disclosing the reforming rolls and the means for feeding the compressed cans thereto. Fig. 2 is a vertical central sectional view taken on line $v-v$ of Fig. 3. Fig. 3 is a

transverse sectional view taken on line $w-w$ of Fig. 1. Fig. 4 is a sectional view taken on line $s-s$ —Fig. 1, disclosing the driving gears for the reforming rolls. Fig. 5 is a transverse sectional view taken on line $x-x$ —Fig. 1, disclosing the configuration of the reforming rolls adjacent the feed end of the machine. Fig. 6 is a transverse sectional view taken on line $y-y$ of Fig. 1, disclosing certain of the side and top reforming rolls. Fig. 7 is a transverse sectional view taken on line $z-z$ of Fig. 1. Fig. 8 is a view in elevation of the discharge end of the machine. Fig. 9 is a perspective view of a flattened can body before the same has been reformed.

Referring more particularly to the drawings, wherein like characters of reference designate corresponding parts throughout the several views, the numeral 1 designates a suitable substantially oblong base, formed in its undersurface with the recess 2. Said base is provided on its upper surface with upwardly projecting bearing studs 3, which are arranged in pairs extending longitudinally of the base and the distance between the studs of each pair decreases from the feed end of the machine toward the discharge end thereof.

A top frame or plate 4, provided with a central opening 4' and carrying corner standards 5 which coöperate with other corner standards 6 extending upwardly from the base 1 is supported above the same, and said frame or plate is formed on its lower surface with downwardly projecting bearing studs 7, one of which is arranged directly above each stud 3 on the base 1, and the distance between the ends of opposing studs 7 and 3 increases from the feed end of the machine toward the discharge end thereof.

Positioned between the ends of the first two pair of opposing studs are vertically disposed reforming rolls 8 carrying at their ends integral shafts 9, which are rotatably mounted in said studs.

Other vertically disposed side reforming rolls 10 are positioned between the ends of opposing studs and also carry shafts 9 which are rotatably mounted in said studs.

The faces of the rolls 8 and 10 are concaved or cut away, as at 10', and the radius of the curvature of the faces increases from the feed end of the machine to a point adjacent to the last pair of vertically disposed rollers at the discharge end, where the radius decreases slightly. The distance between the curved faces of the rollers of each pair decreases from the feed end of the machine 10 toward the discharge end, as in Fig. 3, and the length of the rolls increases from the feed end to the discharge end of the machine.

Suitable top and bottom horizontally disposed reforming rolls 11 are positioned above and below the rolls 10 and said rolls extend between and at their ends touch the ends of the vertically disposed rolls of each pair of side rolls, and are provided at their ends with spindles 12 which are rotatably mounted in the side walls of the studs 7 and 3. The surfaces of the compressing rolls 11 are concaved or cut away, as at 13, as are the faces of the rollers 8 and 10, but the radius of the curvature of the surface of said top and bottom reforming rollers decreases from the feed end of the machine to a point adjacent the last pair of rolls, where the radius increases slightly and is the same as the radius of the vertically disposed reforming rolls. The distance between the curved faces of the top and bottom reforming rolls, increases from the feed end of the machine toward the discharge end thereof, and the length of the rolls decreases from the feed end of the machine toward the discharge end thereof.

It will be apparent that in rear of the first two pair of rollers 8, the rollers are arranged in a series of coöperating top and bottom and side reforming rollers, as in Figs. 6, 7 and 8 of the drawings, and the ends of the curved surfaces of adjacent rolls connect with each other.

45 Certain ends of the reforming rolls 10 and 11 are formed with bevel gears 14 which intermesh with each other, and the lower spindles 9 of certain of the vertically disposed rollers project through the base 1 into the recess 2, and are fitted with gear wheels 15, which intermesh with idlers 16 carried by shafts 17. One end of the supporting spindle 12 of the lower horizontally disposed reforming roll adjacent the feed end 50 of the machine extends outwardly through its stud 3, as at 18, and carries a belt pulley 19 which receives its power from any suitable source and is driven in the direction of the arrow—Fig. 6.

60 It will be apparent that power being applied to the pulley 19, the rotation thereof will rotate the reforming roll keyed thereto and said roll will in turn rotate the other rolls associated therewith, and the rotation

of the rolls will be transmitted through the 65 spindle carrying the gear 15, which in turn will operate the idlers 16 to operate other gears 15.

By arranging the drive mechanism as described, all of the reforming rollers are rotated in the same direction and at the same speed and by a single drive mechanism.

Suitable flat plates 20 are secured between the standards 5 and 6 at the outer side of the vertically disposed reforming 75 rollers 10, and said plates are formed with guide fingers 21 which project inwardly between the reforming rollers and terminate approximately flush with the inner faces thereof. Other plates 22 secured to the 80 upper surface of the base 1 and to the top plate 4 are also provided with guide fingers 23 which project between the horizontally disposed reforming rollers 11 and terminate approximately flush with the inner faces 85 thereof.

The flattened can bodies to be reformed are stacked one above the other in a suitable vertically disposed magazine, positioned adjacent the first pair of reforming rollers 8 90 and said magazine comprises spaced angular corner members 24 secured to the top frame or plate 4 adjacent the feed end, and certain of the corner members 24 are formed in their face adjacent the first pair of rollers 95 8 with a cut out 27 through which the compressed can body is adapted to be passed.

Projecting outwardly from the lugs 26 are the parallel spaced guide shafts 28 on which are slidably mounted the members 29, which are secured to one end of the parallel spaced feeding arms 30 which project in a direction toward the reforming rolls and are bifurcated at their free ends forming a finger 31, which, when the arms are reciprocated in a direction toward the compressing rolls, engage the edge of the lowermost can body and move the same from beneath the stack through the cut outs 27, and into engagement with the reforming rollers 8. 110 The feeding arms are reciprocated by the following mechanism: Pivotaly connected to the member 29 are one end of a pair of links 32, which are respectively pivotaly connected at their opposite ends to the crank arm 33, and the face of the gear 34, said crank arm and said gear being carried at the opposite end of a rotatable shaft 35 mounted in bearings 36 supported by the base 1 adjacent the feed end of the machine 115 120 and said shaft is rotated through a gear 37 carried by the projecting portion 18 of the spindle 12, which intermeshes with the gear 34.

By referring to Fig. 1 it will be observed 125 that the front portions of the fingers are not removed from under the lowermost can body when reciprocated in a rearward direc-

- tion, but are only moved a sufficient distance so that the fingers 31 will be in a position to engage the lowermost body on the next forward reciprocation of the arms.
5. By operating the feeding mechanism by the roller driving mechanism, all parts are so timed as to properly coöperate with each other when operating on a can body, and a compressed can body when fed forwardly 10 from beneath the stack is engaged at its side edges by the rotating rollers 8 which pass the can body to the other side reforming rollers 10, and the top and bottom reforming rollers 11, all of which coöperate 15 to gradually reduce the major axis of the oval can body as the same is passed therebetween until the same reaches the third set of reforming rollers from the discharge end of the machine, which forms the can body 20 into a circle. As the can body passes said last mentioned set of rollers, it is again reformed into an oval, but this time with its major axis in a plane transverse to its former major axis, this being done to insure 25 the working out of the crease along the lines α — α of the body, as in Fig. 9. The body is next passed between the last set of rollers and is again compressed into a true circle, and the rotation of the last set of 30 rollers discharges the reformed can body from the machine in a circular form, and adapted for receiving the ends.
- By my improved machine, I am enabled to rapidly operate on compressed can bodies 35 to restore the same to their original form; have provided a machine in which the reforming means forms a conveyer for the can body in its process or reformation; and have provided a machine which is automatic in 40 all of its operations and one which is thoroughly efficient for the purposes designed.
- Having thus described my invention what I claim as new and desire to protect by Letters Patent is:—
1. In a machine of the class described, the same comprising a reforming matrix through which the can bodies are propelled, the walls of said matrix forming a substantially oval entrance for receiving the compressed can bodies and gradually terminating into a substantially cylindrical discharge opening, and means for feeding can bodies into said matrix.
5. In a machine of the class described, the same comprising a reforming matrix consisting of a plurality of reforming rollers having concaved faces, means for rotating said rollers, means for feeding substantially flat can bodies to one end of said matrix, the rotation of said rollers conveying said can bodies through said matrix and gradually reforming the same into a substantially cylindrical body.
3. In a machine of the class described, the same comprising a reforming matrix open at both ends and consisting of a plurality of reforming rollers having concaved faces, and means for rotating said rollers, the rotation of said rollers conveying said compressed can bodies through said matrix and operating on the same to gradually reform said bodies into substantially cylindrical bodies.
4. In a machine of the class described, the same comprising a reforming matrix open at both ends and consisting of a plurality of rotatably mounted reforming rollers having concaved faces, means for feeding substantially flat can bodies to one end of said matrix, the rotation of said rollers conveying said compressed can bodies between the same and operating on the same to gradually reform said bodies into substantially cylindrical bodies, and means for rotating said rollers in unison and for operating said feeding means.
5. In an apparatus for the described purpose, the same comprising means including rotatable reforming rollers forming a matrix between which a substantially oval can body is received, and means for rotating said rollers for conveying the can body therebetween, said rollers as the body passes through the matrix formed thereby reducing the major axis of said compressed can body until the same is substantially cylindrical in form.
6. In an apparatus for the described purpose, the same comprising reforming means including rotatable rollers forming a matrix and between which a substantially oval can body is received, means for rotating said rollers for conveying the can body therebetween, said rollers as the body passes through the matrix formed thereby reducing the major axis of said compressed can body until the same is substantially cylindrical in form, and means for feeding can bodies to be operated on to said reforming rollers.
7. In a machine of the class described, the same comprising a reforming matrix consisting of a plurality of reforming rollers, means for rotating said rollers, means for feeding substantially flat can bodies to one end of said matrix, the rotation of said rollers conveying said can bodies through said matrix, and gradually reforming the same into a cylindrical body, thence forming the same into a substantially oval body with its major axis in a plane at substantially right angles to its previous major axis, and thence forming said oval body into a substantially cylindrical body.
8. In a machine of the class described, the same comprising a reforming matrix consisting of a plurality of reforming rollers,

means for rotating said rollers in the same direction, the rotation of said rollers conveying said compressed can bodies through said matrix and operating on the same to gradually reform said compressed bodies into substantially cylindrical bodies.

In testimony whereof I have signed my

name to this specification in the presence of two subscribing witnesses.
